HANDLE OR THE LIKE

Dagfinn O. Amdal, Rockford, Ill., assignor to Keystone Consolidated Industries, Inc., Peoria, Ill., a corporation of Delaware

Filed Mar. 10, 1969, Ser. No. 16,143

Term of patent 14 years

Int. Cl. D8—03

U.S. Cl. D8—166

FIG. 2.

FIG. 3.

FIG. 4.

FIG. 5.

FIG. 6.

FIG. 7.

FIG. 2 is a front elevational view thereof;

FIG. 3 is a rear elevational view thereof;

FIG. 4 is an end elevational view thereof showing one position of the handle;

FIG. 5 is an end elevational view thereof showing a second position of the handle;

FIG. 6 is an end elevational view thereof showing a third position of the handle; and

FIG. 7 is a cross sectional view thereof taken on the line 7—7 of FIG. 1.

I claim:

The ornamental design for a handle or the like, substantially as shown and described.
